UNITED STATES PATENT OFFICE

JOSEPH O'CONNELL AND HAROLD HAMILTON KERR, OF KENSINGTON, VICTORIA,
AUSTRALIA

STERILIZER

Application filed October 18, 1927, Serial No. 226,996, and in Australia January 12, 1927.

This invention has been devised to provide a method of and means for sterilizing liquids, the latter during treatment flows through piping in one direction, and opposite to that of the heating medium, one pipe enclosing the other so that during the circulation of both the liquid under treatment and the heating medium, one is raised in temperature and the other reduced; this is owing to the heat 5 of the one being extracted and communicated to the other, the result being that the liquid is discharged reduced in temperature approximately to the same degree when passed into the regenerative section of the apparatus 10 hereinafter referred to.

To ensure the liquid under treatment being thoroughly and effectively sterilized it is advantageous to hold or retard under pressure its flow for a desired period whilst under 15 treatment, this is accomplished by providing any suitable automatic escape or relief valve held nearly shut by any arrangement exerting a definite adjustable pressure so that the valve will allow the liquid to escape when the 20 pressure exceeds a predetermined amount; furthermore the liquid under treatment is gradually and effectively raised and lowered 25 in temperature.

In order that our invention may be the 30 more easily understood, reference will be made to the accompanying sheets of drawings in which—

Fig. 1 illustrates partly in section apparatus embodied in this invention.

Fig. 2 is a plan partly in section and drawn to a large scale of regenerative and heating 35 sections hereinafter described.

Fig. 3 is a sectional view of the said regenerative and heating sections.

Fig. 4 is an end view of apparatus shown 40 in Figs. 2 and 3.

Fig. 5 is a perspective view illustrating the direction of circulation of the liquid through 45 the regenerative and heating sections hereinafter referred to whilst—

Fig. 6 is a view drawn to a large scale of a holding spring hereinafter described.

In the accompanying drawing 1 is a pipe 50 in communication with the source of liquid supply, it being drawn therefrom by a pump

2 of any suitable kind, which forces the liquid through the pipe 2^a into a regenerative section of the apparatus comprising an arrangement of inner and outer tubes 3 and 4 respectively, such tubes being in communication with each other as hereinafter described.

To produce effective sterilization, care must be taken that the leakage of the liquid does not occur through a break or the like in the 60 tubes 3 and 4 of the regenerative section, such possibility is obviated by providing means to allow for the expansion or contraction of the inner tubes 3 of the regenerative section, such tubes are of copper and are free 65 at one or both ends, each of which neatly fits into a hole 6 of a bend 7 with screw plugs 8 positioned in front of each tube 3 (see Fig. 3) to facilitate the cleansing thereof. The bend 7 is disposed within a header 9 bolted to the 70 plate 10 integral with that end of the outer iron pipe 4 whose other end is threaded and screwed home in the respective hole 11 in the plate 12 bolted to the plate 13 of a cover 14, a packing of sheet rubber 13^a being disposed 75 between the said plates 12 and 13. The cover 14 is provided with passageways 14^a for the flow of the liquid as hereinafter described. The exterior of the cover plate 14 has stuffing 80 boxes 15 for centrally positioned ends of the tubes 3, which at this end of the regenerative section project for some distance and each enters a hole 16 of the vertical bend 17 or horizontal bend 17^a, each hole has a stuffing box 18. That end of the tube 3 which delivers the sterilized liquid projects outwardly and enters a loaded valve 19 (see Fig. 1) furnished with suitable means to regulate and control the partly shutting and closing pressure of the valve, preferably a hinged lever 85 20 with an adjustable weight 21 and set screw 21^a is employed. The said lever 20 is mounted on a post 22 integral with the valve casing, the lever 20 resting on the top of the valve stem 23. To steady the lever 20 and also work 90 in conjunction with the weight 21 when the pressure is operating a spring 23^a may be employed, one end being connected to the lever 20 and the other end connected to the 95 projecting end of the tube 3 (see Figs. 1 100

and 6) the tension of the said spring 23^a will be adjusted in accordance with the position of weight 21 on lever 20 by manipulating the threaded unions 22^a to place the threaded members 20^a nearer or further away from each other (see Fig. 6). The regenerative section before referred to is preferably enclosed by a wooden casing 24 packed to surround the tubes 4 with sawdust or other desired insulating medium.

The heating section is in communication with the regenerative section by connecting to the cover 14 the elbow 25 with stuffing box 26 and in which the inner tube 27 is disposed, the said inner tube passes through the stuffing box 28, thence into the outer tube 29, being connected at this point to the stuffing box 28 by the union 30. The outer tube 29 at its other end is attached to a T-piece 30^a which by union and flange constructions 28^a and 29^a is connected to a similar T-piece 31, both T-pieces 30^a and 31 provide communication for the heating agent preferably steam with the other outer tube 29 of the heating section in which the steam enters at 31^a (see Fig. 3) being supplied by the pipe 32 from a boiler 33, the steam being discharged at 34 (see Fig. 3) and returned to the boiler by the pipe 35, both pipes 32 and 35 have cocks 36 for supply control purpose.

It is essential to have an independent supply of steam to the heating section to maintain the pressure of the steam to and through the heating section and the flow of the condensed water from the heating section to the boiler 33. The lower tube of the inner tubes 27 of the heating section adjacent to the T-piece construction before referred to passes through the stuffing box 37 and enters a bend 37^a with stuffing boxes 38 and 38^a, and the upper tube 27 of the heating section is connected to 38^a and passes through a stuffing box 39, connected to the outer tube by the T-piece 31 before referred to, and the other end of the upper tube 27 passes through the stuffing box 37^a connected to the pipe 29 by the union 39^a, the projecting end of the upper tube 27 enters a stuffing box 40 carried by the elbow 41 in communication with a pipe 42 connected by unions 43 to elbow 41 and a similar elbow 44 to which the projecting end of the required inner tube of the tubes 3 of the regenerative section is attached by the stuffing box 45. The tubes 3 and 4 of the regenerative section are arranged in sets of 3 and are parallel (see Fig. 4) the direction of flow of the liquid is shown in Fig. 5, the solid arrows indicate its entry and circulation into and through the tubes 4 and connecting passageways 14^a of the regenerative section and its point of discharge from the heating section is marked A, the dotted arrows show the direction of flow of the liquid from A and whilst circulating through the tubes 3 of the regenerative section to the point marked B.

A thermometer 46^a may be employed to measure the temperature of the liquid as it flows through the tube 27. Upon leaving the regenerative section, after passing through the desired number of tubes 4, the liquid flows through the elbow 25, thence through the inner tubes 27 of the heating section, preferably one coil for the heating section is employed, and during its circulation through such heating section it is raised in temperature by the heating agent, the steam flowing through the outer tube 29 in the opposite direction taken by the liquid, the steam as before stated when discharged from the heating section is returned to the boiler 33.

As the liquid flows from the heating section, and upon reaching the elbow 41, the temperature of the liquid is approximately 220° F. as the liquid continues to circulate under pressure from the pump through the inner tubes 3, within the regenerative section, its flow is gradually retarded for the desired period by the loaded valve 19 disposed on the respective tube of the tubes 3 adjacent to the lower tube 4 and coil of the regenerative section, on passing through the valve 19 the now sterilized liquid flows through the pipe 3 and is led by the branch pipe 19^a into a storage tank or the like 46 with control cock at 47 the projecting end of the pipe 3 beyond the pipe 19^a has a cock at 48 which is closed during sterilizing operations but opened before starting same as may be necessary to clean out the tubes 3 and 4 of liquid in order that unsterilized liquid will not be mixed with the sterilized liquid.

It will be seen from the above that the circulation of the liquid is under pressure which must be maintained, making its flow gradual, and by doing so ensuring an effective treatment of the liquid to provide thorough sterilization thereof.

If it is desired the heating section of the apparatus may be situated at a greater elevation than the boiler in order that the condensed steam may return to the boiler by gravitation.

We would also have it understood that if desired any number of heating and regenerative sections may be employed and the valve and pump aforesaid may be disposed for working operations at any desired point.

Claims:

1. Means for sterilizing liquids, comprising a regenerative section having inner and outer tubes, the inner tubes being free at least at one end, a heating section of inner and outer tubes, the inner tubes being in communication with the outer tubes of the regenerative section, passageways for the circulation of the liquid, and means for retarding the flow of the liquid through the regenerative and heating sections.

2. Means for sterilizing liquids, comprising a regenerative section having inner and

outer tubes, the inner tubes being free at least at one end, a heating section of inner and outer tubes, the inner tubes being in communication with the outer tubes of the regenerative section, passageways for the circulation of the liquid, and means for retarding the flow of the liquid through the regenerative and heating sections, consisting of a valve with stem and hinged lever with 10 adjustable weight and an adjustable spring.

3. Means for sterilizing liquids, comprising relatively high and low heat interchanging means, a sterilized liquid discharge pipe, a weighted valve in said pipe, said valve 15 comprising a lever hinged at one end and bearing upon the upper end of a valve stem, a spring co-acting with said valve to prevent the egress of sterilized liquid when under pressure and to normally retard the flow of 20 liquid through the said pipe, means to adjust the effective response of the valve by the relative tension of said spring and the position of the weight from the fulcrum of the lever and a regenerative portion in the 25 system the inner tubes of which are free at least at one end, as herein-described.

4. Means for sterilizing liquids, comprising a regenerative section of sinuous, concentric spaced tubes, means to supply liquid 30 under pressure to the space between the tubes, in combination with a heating section also comprising concentric, spaced tubes, means to connect the space between the tubes of the regenerative section with one end of the inner 35 tubes of the heater section and connect the other end of the inner tubes of the heater section with the inner tubes of the regenerative section, yielding means at one end of the inner tubes of the regenerator section to 40 normally retard the flow through the latter inner tubes but yielding to pass a greater amount of liquid upon increase of pressure, and means to supply a heating medium to the outer tubes of the heater section.

45 In testimony whereof we have signed our names to this specification.

JOSEPH O'CONNELL.
HAROLD HAMILTON KERR.
